(57) **CLAIM**

The ornamental design for a flexible signal and turn indicator light for a helmet, as shown and described.

DESCRIPTION

FIG. 1 is a front perspective view of a second embodiment of a flexible signal and turn indicator light of the present invention for a larger helmet;

FIG. 2 is a front elevational view of FIG. 1;

FIG. 3 is a rear elevational view of FIG. 1;

FIG. 4 is a first side elevational view of FIG. 1; the second side elevational view being a mirror image thereof; and,

FIG. 5 is bottom plan view of FIG. 1; the top second side elevational view being a mirror image thereof.
